CLOTHES PROP

Harry A. Kearns, Uniontown, Pa.

Application August 2, 1946, Serial No. 687,829

4 Claims. (Cl. 248—353)

1
My invention relates to an improved clothes prop construction having increased strength by the addition of a very substantial guide or support for the sliding extension rod. By these means the height from the ground of a clothes line can be raised quite considerably to be out of the way for drying or airing the clothes which have been hung over the line no higher up than to be conveniently done even by a short person.

My clothes prop is furthermore very neat in appearance and can be handled and positioned easily by one person.

In the accompanying drawing, like numerals refer to the same details in the different views.

Figure 1 is a perspective view of the clothes prop as erected on the ground;

Figure 2 is a view in side elevation of the main prop;

Figure 3 is a similar view of the extension rod which is slidably attached on the main prop;

Figure 4 is a cross section on line 4—4 of Figure 1 with the cleats used to hold the extension rod on the prop;

Figure 5 is a front elevation of a locking lever for clamping the extension rod;

Figure 6 is a section along line 6—6 of Figure 3 of a clip for firmly holding the lever locked; and

Figures 7 and 8 are a side elevation of a modified form of supporting fixture for the extension rod and a cross section thereof along line 8—8, respectively.

In the drawings, reference numeral 10 denotes the main prop of about usual length and preferable square cross section. At its lower end is firmly secured by screws or the like a foot plate 11 which extends forwardly to accommodate the sliding extension rod 12, which is intended to stand thereon in its lowermost position. At the forward edge of the foot plate 11 is provided an upstanding lip 13 at a distance from the face of the prop 10 to prevent the rod 12 from slipping off the foot plate. On its under side the foot plate 11 is provided with a long spike 14 which may have screw threads to facilitate its entering and firm positioning in the ground.

A short distance above the bottom end of the prop 10 a metal cleat 15 is attached by screws or rivets to the prop and having two side arms 16 with inturned fingers 17 for guiding the up and down sliding extension rod 12. Two other metal cleats 15a and 15b are provided, one at the top of the prop 10 and another a short distance therebelow, which have the same function as the cleat 15.

2
A pair of metal supporting plates 18, one on each side of the flat faced prop 10, is secured by rivets or screws a short distance below the cleat 15b. These plates are of some length and at each end they are provided with two forwardly extending arms 19 permitting the extension rod 12 to slide fairly freely between them. The top and bottom edges of said arms are nicked as at 20, 21 intended for engagement with a locking lever 23, carried by the extension rod 12. Lastly, the prop 10 has a knob or handle 29 for gripping the prop when putting it in the ground or lifting it out.

In Figure 3 is shown a side view of the slideable extension rod 12. As here shown the same has square cross section of a size to fit snugly but slidably between the arms 16 of the cleats 15 and between the arms 19 of the side plates 18 to permit the prop to have at least three positions of height on the prop, one with the rod standing on the foot plate 11; another with the lever 23 engaging the lower arms 19 and a third position with the lever engaging the upper pair of arms 19.

The locking lever 23 is hinged as at 24 on a bracket 25 firmly attached as by screws 26 or the like, on the front side of the extension rod 12. The lever 23 is provided with a pair of transversely directed pegs or horns 27, which are long enough to engage one pair with the top nicks 20 and the other pair of pegs 27 with the bottom nicks 21.

The lever 23 has a forwardly and upwardly bent shank beyond said pegs 27 and terminates with a handle 28. When the lever is swung down so that its pegs 27 lock with notches 20 and 21, the lever shank will be gripped between the spring fingers 30 of the clip 31 which is fixed on the rod 12 below the lever bracket 25. In this manner the extension rod becomes firmly locked from both upward and downward movement on the prop 10. It is held upright by the side arms 16, 19 and the fingers 17.

At the top of the extension rod 12 is shown a line gripper provided with a pair of opposing claws 33 bent together with their ends crossing for permitting the easy placing of the clothes line 34 on the prop, but at the same time preventing the line from being jerked or blown off the prop.

The modifications shown in Figures 7 and 8 which are, respectively, side elevation and transverse section on line 8—8 of Figure 7; on the same is shown a guide plate 36 attached to the rear side of the extension rod 12 which engages

under the flanges 18a on the side plates 18. This construction is intended for use on extra long rods 12 to give firm support.

It is to be understood that the invention as herein disclosed may be varied from the details described and shown without departure from the spirit of the subjoined claims.

I claim:

1. An extension clothes prop comprising a main prop and a rod slidably mounted thereon for the purpose of carrying a clothes line at different heights from the ground, guide means for said rod secured spacedly on the main prop and means for securely locking the rod in a plurality of positions to the prop, comprising a series of pairs of nicked arms extending forwardly from said prop and a hinged lever secured on said rod adapted to engage selectively one pair of nicked arms; and transversely projecting pegs on the lever corresponding in position to said nicks.

2. An extension clothes prop comprising a main prop and a rod slidably mounted thereon for the purpose of carrying a clothes line at different heights from the ground, guide means for said rod secured spacedly on the main prop and means for securely locking the rod in a plurality of positions to the prop, comprising a series of pairs of nicked arms extending forwardly from said prop and a hinged lever secured on said rod adapted to engage selectively one pair of the nicked arms; and transversely projecting pegs on the lever corresponding in position to said nicks; and a clip below said lever clamping the lever in locked position.

3. An extensible clothes prop of the character described comprising two rod bodies disposed in side by side relation, one of said bodies carrying a line engaging element at one end, the opposite end of the other body being adapted to position upon the ground, means coupling the rods together for sliding movement, a pair of arms carried by one rod and extending across the other rod to project forwardly from the said other rod, said arms having nicked top and bottom edges, a lever pivotally supported upon said other rod to pass between said arms, the pivotal axis of the lever being perpendicular to the arms, and means carried by the lever for simultaneous engagement in the nicks in the top and bottom edges of the pair of arms.

4. An extensible clothes prop of the character stated in claim 3, with friction holding means carried by the rod upon which the lever is mounted, for receiving and frictionally holding the lever in arm engaging position.

HARRY A. KEARNS.
